UNITED STATES PATENT OFFICE.

MEYER L. ROBBINS, OF NEW YORK, N. Y.

DESIGN FOR A CUT GEM.

45,353.

Specification for Design.

Patented Mar. 3, 1914.

Application filed December 12, 1913. Serial No. 806,336. Term of patent 7 years.

To all whom it may concern:

Be it known that I, MEYER L. ROBBINS, a citizen of the United States, residing at New York city, in the county of New York and State of New York, have invented a new, original, and ornamental Design for Cut Gems, of which the following is a specification, reference being had to the accompanying drawing, forming part thereof.

Figure 1 is a plan view of a cut gem,

Fig. 2 an elevation and Fig. 3 a bottom view, showing my new design.

I claim:

The ornamental design for a cut-gem, as shown.

MEYER L. ROBBINS.
